UNITED STATES PATENT OFFICE.

EDWARD GRUBER, OF LYNDHURST, OHIO.

UNIT FOR TRACK BELTS.

Carved out of application on which Patent No. 1,359,499 was granted November 23, 1920, and filed after grant of the patent. This application filed March 8, 1922. Serial No. 542,119.

To all whom it may concern:

Be it known that I, EDWARD GRUBER, a citizen of the United States, residing at Lyndhurst, in the county of Cuyahoga and 5 State of Ohio, have invented a certain new and useful Improvement in Units for Track Belts, of which the following is a full, clear, and exact description.

This invention is matter carved out of 10 applicant's Patent 1,359,499 and is an improvement upon the unit or link which is shown and described in Patent 1,317,896 to E. H. Savage dated Oct. 7, 1919, the principal object being to increase the strength 15 and durability of the link sides of the unit, and to diminish the chance that the horizontal flanges at the upper edges of said link sides, which serve as bearing surfaces or rail tops for the track wheels shall be so much 20 tilted and deformed in use that they can not satisfactorily serve the purpose for which they are provided.

The invention consists in the combination 25 of parts shown in the drawing and hereinabove described, as definitely pointed out in the appended claims.

In the drawings Figure 1 is a top plan view of the track unit embodying the invention; Fig. 2 is a side elevation of the 30 track unit; and Fig. 3 is a front elevation of the same partly broken away and sectioned.

The link comprises three members, viz: the middle member A and the two side members B and C, all made from metal sheets bent into the forms shown and secured together. The middle member A has the form of a substantially square U, and is so formed by bending up the sides of the metal plate, 40 thereby producing the flat bottom or shoe portion 12, and the two vertical longitudinally extended rails 13.

The two side members B and C are alike except that they are right and lefts. Each 45 has a vertical longitudinally extended rail 21. These rails are so shaped that when the three pieces are placed side by side the rails 13 and 21 will be in contact near the front end of the unit, and near the rear end of the 50 unit; but the parts of the rails between said contacting front and rear ends are spaced apart. This results from the fact that the rails 13 near their rear ends are offset apart; and the rails 21 near their front ends are offset toward one another. The offset por-

tions are, however, parallel with each other and with the rails from which they are offset. When the rails are placed together as stated, the offset front ends of the rails 21 engage with the outer faces of the front ends 60 of the rails 13 and are connected with them by spot welding, rivets and the like. The offset rear ends of the rails 13 will likewise engage the inner faces of the rails 21, and these engaging parts are connected together 65 by spot welding, rivets or the like.

The offset parts of said rails at the front and rear ends of the unit, together with the parts of the rails which contact with and are secured to said offset parts constitute double 70 thick ears. These ears at the rear ends of the unit are farther apart than those at the front end of the unit; and therefore the ears at the front end of the unit may go between the ears at the rear end of the adjacent unit; 75 and the overlapping ears may be pivoted together by any suitable or well known means.

In the construction shown a shoe 30 is provided and is connected to the base of the middle member A, by spot welding, rivets, 80 or the like.

The upper edges of the rails are formed with turned over horizontal flanges 24; and these flanges rest only on the top of the offsetting web 25 of the rails 21. These 85 flanges 24 form strong, well braced, broad surfaces for the track wheels to ride on, and they are so constructed and supported that there is practically no chance that they will become deformed by use to an extent, such 90 as will render them insufficient for the purpose for which they are provided.

The front edge of the shoe 30 may be turned down to form the ground engaging rib or grouser 31.

Having described my invention, I claim:

1. In a track belt unit, a shoe, a central rail member having a bottom secured to said shoe and bent up sides forming rails, said rails having flanges extending therefrom, and side rail members secured to the sides of said central rail member supporting the flanges extending therefrom.

2. In a track belt unit, a shoe, a central 105 rail member having a bottom secured to said shoe and bent up sides forming rails, and a side rail member secured to and adjacent the outer sides of each of the sides of said central rail member.

3. In a track belt unit, a shoe, a central under and supporting a portion of the rail member having a bottom secured to said shoe and bent up sides forming rails, said rails having flanges extending therefrom, and side rail members secured to the sides of said central rail member, said side rail members having an offset web extending

10

In testimony whereof, I hereunto affix my signature.

EDWARD GRUBER.
